UNITED STATES PATENT OFFICE.

PETER P. KIEL, OF OAKLAND, CALIFORNIA.

WASHING-MACHINE.

SPECIFICATION forming part of Letters Patent No. 790,639, dated May 23, 1905.

Application filed August 16, 1904. Serial No. 220,895.

To all whom it may concern:

Be it known that I, PETER P. KIEL, a citizen of the United States, residing at 224 San Pablo avenue, Oakland, in the county of 5 Alameda and State of California, have invented certain new and useful Improvements in Washing-Machines, of which the following is a specification.

My invention relates to improvements in 10 washing-machines, the object of my invention being to provide a washing-machine especially adapted for washing clothes in stationary wash-tubs with which modern houses are now commonly provided. In devising such a machine it has been my object to make it light 15 and portable, so that it can be easily moved to or from the tub.

My invention therefore resides in the novel construction, combination, and arrangement 20 of parts for the above ends, hereinafter fully specified, and particularly pointed out in the claims.

In the accompanying drawings, Figure 1 is a perspective view of my improved washing- 25 machine in the position of use. Fig. 2 is a section of the dasher.

Referring to the drawings, 1 represents stationary wash-tubs with which my invention is intended to be used.

2 represents a foot-board placed on the floor opposite to the tub in which the washing is to take place, and on a bar 3 on said foot-board is pivoted a foot-lever 4, the upward movement of which is limited by an angular stop 35 5, secured to the foot-board and to one of the braces 6 of a vertical post 7, erected on the foot-board at one corner thereof, as shown. Upon the upper end of said post is swiveled, as shown at 8, a fork 9, in which is pivoted 40 an arm 10, which extends in both directions from said pivot, the rear end of the arm being attached by a spring 11 to a staple 12 at the lower end of the post. This spring normally draws the rear end of said arm downward and the front end upward. The front portion of the arm is connected with the foot-lever by a metallic rod 13, said arm being notched, as shown at 14, to vary the point of attachment of the rod thereto. At the extreme front end of said arm is pivotally at-

tached a dasher-rod 15, carrying at its lower end a dasher 16.

The operation of the device is as follows: The operator stands upon the foot-board with his left foot, places his right foot upon the 55 foot-lever, rests his right arm upon the arm 10, and holds the dasher-rod with his left hand. Then by vibrating the foot-lever with his foot against the action of the spring he causes the dasher to descend into and rise from the tub 60 alternately, lifting the clothes out of the water by suction at each ascent of the dasher and when the clothes drop from the dasher and the dasher again descends into the water forcing air from said dasher through the 65 clothes. By means of his right arm and left hand he has complete control of the dasher and can direct it to any part of the tub desired. This is permitted especially by the 70 swivel connection of the fork with the upright post, which permits the arm to be moyed horizontally around said post.

This machine allows nearly the whole of the force used in washing to be applied by the foot instead of by the hand, the hands being 75 only to guide and control the force so applied, and thus the labor of washing is very greatly reduced. It will also be seen that the device is of simple construction, of parts easily made, and not liable to get out of order, and, moreover, is comparatively light, so that it can be easily moved from place to place.

I claim—

1. A washing-machine comprising a foot-board, a lever pivoted on said foot-board, a post standing on the rear portion of the board, an arm pivoted at the upper part of said post and extending forward to a point over the front portion of the foot-board, a dasher-rod 85 secured to the front end of said arm, a dasher carried by said dasher-rod, a connection between the lever and the arm between the dasher-rod and the post, and a spring operating to raise said lever, substantially as described.

2. A washing-machine comprising a foot-board, a foot-lever pivoted at the rear of the board and extending toward the front end thereof, a post at the rear end of the board, 90

100

an arm pivoted on the top of said post and extending to a point over the front portion of the board, a link between said lever and arm, a dasher carried by the front end of said arm, 5 and a spring raising said lever, substantially as described.

3. A washing-machine comprising a foot-lever, a post, a support adapted to rest upon the ground to which said post is rigidly secured, said support extending from said post in the general direction of said foot-lever an arm pivoted on the upper end of said post, a dasher-rod secured to the end of said arm, a

dasher carried by said dasher-rod, a connection between the lever and the arm between 15 the dasher-rod and the post, and a spring operating to raise said lever, substantially as described.

In witness whereof I have hereunto set my hand in the presence of two subscribing witnesses.

PETER P. KIEL.
